UNITED STATES PATENT OFFICE.

EDWARD MEMLEB, OF NEW YORK, N. Y.

DESIGN FOR A FRINGE-HEADING.

SPECIFICATION forming part of Design No. 16,097, dated May 19, 1885.

Application filed March 3, 1885. Term of patent 7 years.

To all whom it may concern:

Be it known that I, EDWARD MEMLEB, of the city, county, and State of New York, have invented and produced a new and original Design for a Fringe-Heading, of which the following is a full, clear, and exact description.

Reference is to be had to the accompanying drawing, forming part of this specification, in which a face view of my new design for fringe-heading is shown.

The leading feature of my design consists in a fringe-heading having a series of ornaments presenting the appearance of groups of united tufts, a space being left between each group.

In the drawing, A represents the heading,

and B the fringe depending therefrom. C are the ornaments, composed of groups of united tufts D on the heading.

What I claim as new, and desire to secure by Letters Patent, is—

The design herein shown and described, the same consisting, essentially, in a fringe-heading having groups of three or more united tufts, producing fancy figures in the said heading, the said groups being each separated a greater or less distance from the other groups on the same heading.

EDWARD MEMLEB.
